Primary Examiner — Dominic Simone(74) *Attorney, Agent, or Firm* — Craig R. Miles; CR Miles, P.C.(57) **CLAIM**

The ornamental design for a three-toed shoe, as shown and described.

DESCRIPTION

FIG. 1 is a top and right side perspective of a three-toed shoe design showing my new design;
 FIG. 2 is a front elevation view thereof;
 FIG. 3 is a rear elevation view thereof;
 FIG. 4 is a left side elevation view thereof;
 FIG. 5 is a right side elevation view thereof;
 FIG. 6 is a top plan view thereof; and,
 FIG. 7 is a bottom plan view thereof.
